UNITED STATES PATENT OFFICE.

HARRY STILLSON HART, OF CHICAGO, ILLINOIS, ASSIGNOR TO RODGER
BALLAST CAR COMPANY, OF CHICAGO, ILLINOIS, A CORPORATION OF
ILLINOIS.

FREIGHT-CAR.

No. 799,646.

Specification of Letters Patent.

Patented Sept. 19, 1905.

Application filed June 27, 1904. Serial No. 214,294.

To all whom it may concern.

Be it known that I, HARRY STILLSON HART, a citizen of the United States, residing at Chicago, in the county of Cook and State of Illinois, have invented certain new and useful Improvements in Freight-Cars, of which the following is a specification.

This invention relates particularly to a freight-car which can be used either as a longitudinal hopper-car for carrying coal, ore, or other material in bulk or as a flat-top or platform car for miscellaneous freight and which is convertible from one to the other at will.

The principal object of the invention is to provide a simple, economical, and efficient convertible dump-car, as will more fully hereinafter appear.

The invention consists principally in a convertible car in which there are combined a supporting-frame portion, a hopper-bottom secured thereto and extending below the same, movable side and end portions arranged to form the sides and ends of a dump-car in one position and a platform-car in a second position, and movable stakes for bracing the sides of the car and adjustable below the floor-line thereof, thus forming a substantially flat unobstructed flooring when said sides, ends, and stakes are in folded position.

The invention consists, further and finally, in the features, combinations, and details of construction hereinafter described and claimed.

In the accompanying drawings, Figure 1 is a plan of my convertible car, showing one half of the car as erected to form the hopper and the other half with the movable parts of the hopper entirely removed and disclosing the underframing; Fig. 2, a plan of the car converted to a platform-car; Fig. 3, a partial side view and partial longitudinal section of the car, showing it as a hopper-car; Fig. 4, a side elevation showing the invention as a platform-car; Fig. 5, an end elevation showing one side of the car as a hopper and the other as a platform car, and Fig. 6 a transverse vertical section showing one side as a hopper and the other as a platform car.

In the drawings the car is shown as pro-

vided with side sills 10, intermediate sills 11, a center sill 12 in the form of an inverted-T beam, needle-beams 13, end sills 14, transom 15, and supplemental intermediate sills 16, located between sills 11 and 12, but in a lower plane. The sills 10 and 11 extend from end to end of the car, but the sills 12 and 16 are entered or bolted at their ends in 60 or to cross-beams 17, which connect sills 11 and 16 and are also bolted to longitudinal timbers or beams 18.

Below the level of the sills are the permanent parts of the hopper—to wit, the full side 19, partial side 20, dumping-door 21, and ends 22. The parts 19, 20, and 21 are supported upon the intermediate and supplemental sills and the ends 22 by the cross-beam 17. The door is held closed by chains 70 23 and winding-shaft 24, the latter being provided with a ratchet-wheel 25, pawl 26, and operating-lever 27.

The movable parts of the car sides consist of a series of planks 28, which can be used to 75 form a hopper, as shown, united at proper intervals by angle-irons 29 and top planks 30, and they are sustained in their raised position by a series of foldable stakes 31. These stakes are bolted to the sills 10 by bolts 33 80 and 34 and to plank 30 by bolts 35 and 36, and also to the angle-irons 29, as seen at 32, Fig. 6. The irons 29 are also bolted, when the hopper sides are raised, by bolts 37 to L-shaped metal pieces 38, secured to the intermediate sills 11.

To lower the movable sides in effecting conversion from a hopper to a platform car, the stakes are released from the hopper sides by taking out the bolts 32, 35, and 36 and 90 also removing the upper bolts 33, connecting the stakes to the sills, and are then turned sidewise on the bottom bolts 34 to the position shown in Fig. 4, where they are, as it were, adjusted entirely below the level of the 95 car-floor. The bolts 37 being also removed, the sides 28 and 30 can then be positioned, as shown at the left of Fig. 6, with plank 30 at the outer edge, and form the floor or flat top of the car. In this changed position the longitudinal pieces of angle-iron 280, with which the lowermost planks 28 are furnished, and which extend between the adjacent pairs of vertical ribs 29, are bolted to the central in-

verted-T metal sill 12, as shown in said figure, and the ribs 29 rest upon the intermediate sills 11. The top planks 30 are positioned upon the side sills, with their inner edges resting on the ribs 29, as at Fig. 6, and they, together with the plank 28 of the two sides, form a flat floor extending from side to side of the car.

The movable ends of the car consist of 10 planks 42, held together by angle-iron ribs 41 and top planks 40, and they are supported to form the hopper by end stakes 43, bolted to the beams 18. The ribs 41 are bolted to the stakes by bolts 44 and are also 15 attached to the beam 17 by suitable fastenings (not shown) and serve as braces to transmit the end thrust of the load to said beam and the center sill. The top planks 40 are bolted directly to said end stakes by bolts 45. 20 To lower the hopper ends, the bolts 44 and 45 are removed and the stakes 43 are detached from the car, thus permitting the planks 40 and 42 to be positioned horizontally, as in Fig. 2. They thus complete the floor of the 25 car, with the exception of the angles 46, 47, 48, and 49, which are covered by permanent flooring-pieces, though the piece 49 should be removable to give access to the chain-operating lever 27.

30 By this construction the car can be used as a platform or a hopper car, as desired, and be changed from one to the other at will, and the only parts employed in the hopper-car which are detached and not used in the platform-car are the end stakes.

The top planks 30 and 40 are useful in the hopper mainly to increase its capacity, and they may, if preferred, be permanently attached to the frame of the car instead of being 40 changeable in position, and in such case the stakes should be shortened.

The ends of sill 12 are secured to cross-beam 17 by a metal union 50, bolted to the beam by bolts 51 and having one end forked 45 and bent to conform to and embrace the web of sill 12, to which such ends are bolted by the bolt 52.

I claim—

1. In a car of the class described, the combination of a supporting-frame portion, a hopper-bottom secured thereto and extending below the same, movable side and end portions arranged to form the sides and ends of a dump-car in one position and a platform-car in a second position, and movable stakes for bracing the sides of the car and adjustable below the floor-line thereof, thus forming a substantially flat unobstructed flooring when said sides, ends and stakes are 55 in folded position, substantially as described.

2. In a car of the class described, the combination of a supporting-frame portion, a hopper-bottom secured thereto and extending below the same, movable side and end

portions adapted when in one position to 65 form the side and end portions of a hopper-car and in a second position to form the flat bottom of a platform-car, and adjustable stakes pivotally connected to the body of the car and radially movable thereon so as 70 to brace the sides of the car when in one position and to be moved below the floor-line of the car when in a second position, substantially as described.

3. In a car of the class described, the combination of a supporting-frame portion, a hopper-bottom secured thereto and extending below the same with its apex arranged longitudinally of the car and at or near the longitudinal center thereof, movable side 80 and end portions adapted when in one position to form a portion of the sides and ends of a hopper-car and when in another position to form a complete flat-floor platform-car, and a plurality of movable side stakes pivotally secured to the side frame of the car for bracing the sides, arranged to form a hopper-car and adjustable beneath the floor-line so as to form a flat unobstructed platform-car, substantially as described.

4. In a car of the class described, the combination of a supporting-frame, a hopper therefor formed of fixed portions provided with a dumping-hopper door-frame and extending below the same and movable portions extending above the same so as to form a portion of the sides and ends of the hopper when in one position and complete a flat-floor platform-car when in a second position, end stakes for supporting the end portions, foldable side stakes pivotally secured to the frame of the car for bracing and holding the side portions of the hopper in position and adapted to be folded below the floor-level of the car when in the second position, 100 and upper side and end boards 30 and 40 secured to the upper ends of the side and end stakes respectively for bracing and assisting to hold the stakes and thereby the sides and ends of the car in position, substantially as 105 described.

5. In a car of the class described, the combination of a frame portion provided with a center sill of inverted-T irons acting to support the movable sides of the hopper when 115 lowered to form the floor of a platform-car, and movable portions adapted to form the sides of the car in one position and part of the flat floor in a second position, substantially as described.

6. In a car of the class described, the combination of a frame portion provided with changeable hopper sides carrying angle-irons 29, and a center sill to which said irons may be bolted substantially as described.

7. In a car of the class described, the combination of a car-frame having inclined ends provided with vertical ribs 41 supported at

the top by end stakes and at the bottom by cross-beams 17 and acting as braces to enable the stakes to sustain the end thrust of the load in the hopper, substantially as described.

5 8. In a car of the class described, the combination of a frame portion provided with a

center sill, cross-beams 17 and a metal union 50, substantially as described.
